DESIGN FOR A COMBINED STAND AND TRAY FOR SMOKERS

Miner G. Ketchum, Indianapolis, Ind.

Application April 20, 1935, Serial No. 56,486

Term of patent 3½ years

To all whom it may concern:

Be it known that I, Miner G. Ketchum, a citizen of the United States of America, residing at Indianapolis, in the county of Marion and State of Indiana, have invented a new, original, and ornamental Design for a Combined Stand and Tray for Smokers, of which the following is a specification, reference being had to the accompanying drawing, forming part thereof.

Figure 1 is a side elevational view of the stand embodying my new design; Figure 2 is a top plan view thereof, and Figure 3 is a front elevational view of the stand.

I claim:

The ornamental design for a combined stand and tray for smokers, as shown.

In testimony whereof I affix my signature.

MINER G. KETCHUM.
